United States Patent Office

Des. 202,309
Patented Sept. 14, 1965

202,309

TOOL FOR EMBOSsing STRIPS OF MATERIAL

Burnie M. Craig, Pasadena, Calif., assignor to Avery Products Corporation, San Marino, Calif., a corporation of California

Filed Aug. 10, 1964, Ser. No. 81,231

Term of patent 14 years

(Cl. D64—10)

FIG. 1.

FIG. 2.

FIG. 3.

FIG. 4.

FIG. 5.

FIG. 1 is a side elevational view of a tool for embossing strips of material showing my new design, the other side being substantially the same;

FIG. 2 is a top plan view thereof;

FIG. 3 is a front elevational view of FIG. 1;

FIG. 4 is a rear elevational view of FIG. 1; and

FIG. 5 is a bottom view of FIG. 1.

The dominant features of my design reside in these portions shown in full lines on the drawing.

I claim:

The ornamental design for a tool for embossing strips of material, as shown and described.
